UNITED STATES PATENT OFFICE.

HUGH B. BOOKOUT, OF SHERMAN, TEXAS.

HOG-TROUGH.

No. 806,317.

Specification of Letters Patent.

Patented Dec. 5, 1905.

Application filed July 15, 1905. Serial No. 269,831.

To all whom it may concern:

Be it known that I, HUGH B. Bookout, a citizen of the United States, residing at Sherman, in the county of Grayson and State of Texas, have invented certain new and useful 5 Improvements in Hog-Troughs, of which the following is a specification.

This invention embodies a novel form of hog-trough; and the invention includes, essentially, a peculiar construction of framework and operating means for the trough whereby the latter may be transported conveniently from place to place, the operating means aforesaid being designed to admit of 15 raising or elevating the trough, so as to fill the same with feed without interference of the animals. The operating means is also designed to facilitate tilting of the trough in emptying and cleaning the same, as will be 20 pointed out more clearly hereinafter.

For a full description of the invention and the merits thereof and also to acquire a knowledge of the details of construction of the means for effecting the result reference 25 is to be had to the following description and accompanying drawings, in which—

Figure 1 is a perspective view of a trough embodying the invention, the same being elevated and tilted. Fig. 2 is a vertical longitudinal sectional view of the trough and adjacent framework in which it is mounted. Fig. 3 is a top plan view. Fig. 4 is an end elevation.

Corresponding and like parts are referred 35 to in the following description and indicated in all the views of the drawings by the same reference characters.

Specifically describing the invention, the numeral 1 indicates the trough, and the same 40 is of any suitable form for feeding a number of animals. The trough is mounted in a framework including spaced pairs of uprights 2 and 3, the latter extending upwardly from transverse beams 4, connected by longitudinally-spaced sills 5. Suitable braces 6 are provided for bracing the uprights 2 and longitudinal bars 7, which connect the upper 45 ends of the pairs of uprights 2 and 3. Transverse bars 8 connect the longitudinal bars 7, 50 which latter incline upwardly toward a point approximately central of the ends thereof.

The means for raising and lowering the trough 1 includes a windlass comprising the drum 9, mounted in suitable bearings carried by the bars 7, said drum being connected 55 by suitable cables or ropes 10 at opposite

ends of the trough 1. The windlass-drum 9 is adapted to be turned by means of a crank-handle 11, suitably attached to an end thereof and arranged upon the outer side of one of the longitudinal bars 7, and a pawl 12 is arranged to engage ratchet-teeth 13 at one end of the drum to prevent the drum from backward rotation after the trough 1 has been elevated. A handle 14 for the pawl 12 admits of convenient disengagement of the pawl from the ratchet-teeth 13, so that the trough may lower until it rests upon the transverse beams 4 at opposite ends of the framework above described.

When resting on the beams 4, the trough is arranged between the longitudinal sills 5 and is therefore not likely to be moved by the animals as they are feeding. Further, the trough is prevented from longitudinal movement between the sills 5 by the provision of transverse cleats 15, suitably attached to the under side of the bottom of the trough and adapted to abut with the inner sides of the beams 4 and form stops to limit 75 the movement of the trough, in an obvious manner. The ends of the cleats 15 are beveled and incline upwardly and outwardly, so that as the trough lowers said ends may engage with the longitudinal sills and centralize 80 the trough to facilitate positioning of the same upon the beams 4.

The ropes 10, connecting the drum 9 with the ends of the trough 1, pass over rollers 16, journaled between the upper ends of the pairs 90 of end uprights 2 and 3.

In order to facilitate the operation of cleaning out the trough, it is designed that the same may be raised a predetermined distance until one side thereof engages with pins 17, 95 which project from the inner sides of one of each of the opposite pairs of uprights 2 and 3, said pins coöperating with the adjacent side of the trough to cause the same to tilt toward one side when it is raised to a sufficient height, and a handle 18, attached to the side of the trough opposite that which engages the pins 17, may be readily grasped by the operator, so as to assist in tilting the trough, as above described. In order that 100 the trough may tilt, it is necessary that the uprights 2 and 3 be spaced apart near the upper portions thereof a distance somewhat greater than the width of said trough, and in order that the trough may assume its normal 110 position between the sills 5 when lowered it is designed to provide guides 19, arranged

upon the inner side of one of each pair of uprights 2 and 3. The guides 19 consist of strips of suitable length having the upper portions thereof beveled, so that the bottom 5 of the trough engaging the beveled portions (indicated at 20) will cause the trough to move readily into the space between the guides 19 and the opposite uprights as it is lowered to rest upon the beams 4.

10 The operation of the invention is very simple, since it is only necessary to turn the crank-handle 11 to raise the trough to a position where it may be readily filled without being disturbed by the crowding of the animals which are to be fed. A paddle 21 is arranged upon the upper portion of the framework above one of the bars 7, being held in place by U-shaped holding members 22, and this paddle may be used in distributing the 15 feed properly in the trough. Further, in cleaning the trough the same is raised until the pins 17 engage a side thereof and cause it to tilt on further upward movement, and the handle 18 may be grasped to assist the tilting 20 movement. The paddle 21 is of course convenient for use in cleaning out the trough 25 also.

The invention possesses various advantages which will be apparent without further 30 recitation. A shelf 23 is carried by one of the uprights comprised in the framework and is adapted to support a bucket or similar receptacle in which feed is carried to the trough or which is used in any similar way.

35 Having thus described the invention, what is claimed as new is—

1. In combination, a framework, a trough mounted therein, a windlass mounted in the framework and connected with the trough 40 for raising and lowering the same, and members projected from the framework and adapted to engage a side of the trough to tilt the same at a predetermined point in its upward movement.
- 45 2. In combination, a framework, a trough mounted therein, a windlass carried by the framework and connected with opposite ends of the trough to raise and lower the same, pins projected from the framework and 50 gaging a side of the trough to tilt the same at

a predetermined point in its upward movement, and a handle carried by the trough at the side opposite that adapted to engage with the pins aforesaid.

3. In combination, a framework embodying spaced pairs of uprights, transverse beams adjacent said pairs of uprights, longitudinal sills connecting said beams, a trough adapted to rest upon the beams and between the longitudinal sills, means for raising and lowering the trough, and means upon the under side of the trough for preventing longitudinal displacement thereof.

4. In combination, a framework embodying spaced pairs of uprights, transverse beams 65 adjacent said pairs of uprights, longitudinal sills connecting said beams, a trough adapted to rest upon the beams and between the longitudinal sills, means for raising and lowering the trough, and transverse cleats upon 70 the under side of the trough and adapted to engage the transverse beams to prevent longitudinal movement of the trough when resting thereon, said transverse cleats having the ends thereof beveled outwardly and upwardly 75 to coöperate with the longitudinal sills to centralize the trough between the uprights.

5. In combination, a framework embodying spaced pairs of uprights, transverse beams adjacent said pairs of uprights, longitudinal 80 sills connecting said beams, a trough adapted to rest upon the beams and between the longitudinal sills, means for raising and lowering the trough, transverse cleats upon the under side of the trough and adapted to engage the transverse beams to prevent longitudinal movement of the trough when resting thereon, said transverse cleats having the ends thereof beveled outwardly and upwardly 85 to coöperate with the longitudinal sills to centralize the trough between the uprights, and 90 guide members attached to one of each pair of uprights to engage the trough in its downward movement, for the purpose specified.

In testimony whereof I affix my signature 95 in presence of two witnesses.
